VIBRATOR CURRENT-CONVERTING
SYSTEM

William W. Garstang, Indianapolis, Ind., assignor to Electronic Laboratories, Incorporated, Indianapolis, Ind., a corporation of Indiana

Application July 17, 1940, Serial No. 345,996

6 Claims. (Cl. 175—365)

The present invention relates to a vibrator system for converting direct current into alternating current.

In systems of this character and particularly in those systems which have heretofore commercially been used, wherein a vibrator switch including a resiliently mounted movable contact adapted to break and make engagement with fixed contacts on either side thereof and wherein at least one capacitor has been used and adapted to be charged periodically through the vibrating switch from the direct current source or battery and wherein an output transformer is provided, the secondary being connected to the load and primary of which is adapted to be energized periodically through the vibratory switch from the capacitor, certain objections have been found. Among these objections is, one, the comparatively low output of the system; and, two, due to the fact that there are times when, if for any reason the vibrator reed should become stuck on its initial movement, the system as a whole will become inoperative.

It is one of the objects of my present invention to provide a system having the above-mentioned characteristics without the above-mentioned objections.

By my present invention, I am able to provide a system wherein, through the control of the vibrator, the secondary of the transformer will be charged through the discharge of the capacitor more effectively to thereby increase the output and, at the same time, the danger of inoperativeness as a result of the reed sticking on its initial movement, is prevented.

For the purpose of disclosing my invention, I have illustrated certain embodiments thereof in the accompanying drawing, in which:

Fig. 1 is a diagrammatic view of a current-converting system, including a capacitor for energizing the output circuit winding embodying my invention;

Fig. 2 is a diagrammatic view of a modification of the system illustrated in Fig. 1; and

Fig. 3 is a diagrammatic view of a still further embodiment of my invention wherein the load is disclosed as being in the nature of a clock motor or equivalent structure.

Referring to Fig. 1, the vibrating or vibratory switch 1 comprises a vibratory element including a pair of resilient reeds 2 and 3, each having respectively thereon contacts 4 and 5. The contacts 4 have arranged on opposite sides thereof stationary contacts 6 and 7 and the contacts 5 likewise have on opposite sides thereof stationary

contacts 8 and 9. The reeds 2 and 3 are preferably connected together by a suitable armature member 10 secured at their outer ends but insulated from the reeds and subject to the influence of an actuating winding 11. The stationary contacts 7 and 8 are connected to one terminal of a capacitor 12 which should be of the alternating current type, i. e., it should be of a non-polarized type. The opposite terminal 10 of the capacitor 12 is connected to the primary winding 13 of an output transformer 14, the secondary 15 of which is connected to the load. The opposite terminal of the primary 13 is connected respectively to the stationary contacts 6 and 9 of the vibrator switch. In addition to the above-mentioned contacts on the vibrator switch, the reed member 2 of the switch is provided with a contact 16 normally in engagement with a stationary contact 17. This reed 2 is connected with one terminal of a source of direct current in the present instance comprising the battery 18. The stationary contact is connected with one terminal of the winding 11 and the opposite terminal of this winding is connected to the opposite terminal of the battery 18. The reed 2 is connected to one terminal of the battery 18, and reed 3 is connected to the opposite terminal of the battery 18.

In operation, with the contacts 16 and 17 normally closed, the winding 11 will be energized from the battery 18 through these contacts, thereby moving the vibrator reeds 3 and 2, as a unit, in a direction to open contacts 16 and 17 and in a direction to engage contacts 4 and 5 on the reeds 2 and 3 with the contacts 7 and 9. The closing of contacts 4 and 7 and 5 and 9 immediately establishes a circuit through the capacitor 12 from one side of the battery to the opposite side of the battery, whereby a charging current flows into the capacitor 12. At the same time that contacts 4 and 7 and 5 and 9 are closed, contacts 16 and 17 are open, thereby opening the circuit of winding 11 and releasing the reed unit, opening contacts 4 and 7 and 5 and 9, thereby causing the capacitor 16 to discharge and energize the primary winding 13. The vibrator movement of the reed unit is such as to swing it in the opposite direction closing contacts 4 and 6 and contacts 8 and 5. In this swinging movement, contacts 16 and 17 are again closed. The closing of contacts 4 and 6 and 5 and 8 establishes an energizing current to the capacitor 12 in the opposite direction and, at the same time, the closing of contacts 16 and 17 re-energizes the winding 12 causing the vibrator to again swing

in the opposite direction opening contacts 4 and 6 and 5 and 8, and thus causing the capacitor 12 to discharge through the primary winding 13 of the transformer in the opposite direction.

The above construction contemplates that the natural vibration frequency of the vibrator element or unit comprising the reeds 2 and 3 is substantially equal to the frequency to which the series circuit including the winding 13 and the capacitor 12 tunes. In actual practice, I have found that although theoretically the vibration frequency of the reed element is the same as the frequency to which the series circuit tunes, more advantageous results are obtained if the natural vibration frequency of the vibrating element is less by a predetermined amount than the frequency to which the series circuit tunes. By providing for this slight differential, the current through the switch 1 at the closed contact periods is reduced to zero before the contacts open and sparking at the contacts is practically eliminated.

In Fig. 2, I have illustrated a modification of the structure illustrated in Fig. 1 wherein, in order to reduce sparking at the contacts controlling the circuit through the energizing winding 11, I have introduced in the circuit of this energizing winding a resistance 19. The value of this resistance is relatively high but is sufficiently low to pass sufficient energizing current for the coil 11.

In the structure illustrated in Fig. 3, I have shown a still further modification of the invention. In this structure, the load consists of a small alternating current electric motor or its equivalent. The secondary 13' constitutes the stationary windings of the alternating current self starting electric motor and, in effect, the secondary comprises the rotor winding 20.

In each of the structures illustrated, however, it will be noted that I have provided what may be termed a series circuit including a capacitor which is alternately charged and discharged in opposite directions through the medium of a vibrating switch, and that I have also provided a circuit for operating the vibrating switch which is independent of the series circuit so that at no time is there danger of failure of the vibrator to operate as would be the case if, for instance, the capacitor were included in the circuit of the energizing coil of the vibrator at some period.

I claim as my invention:

1. In an electric system for converting direct current into alternating current, said system having a transformer with input and output windings, a source of direct current supply, a series input circuit including said input winding, a capacitor and a vibratory reed switch having movable contacts on said reed cooperating with stationary contacts to alternately connect said input circuit including said input winding and capacitor with said source of direct current in opposite directions, the vibrating frequency of said reed being substantially the same as the frequency to which said series circuit is tuned to effect the opening of said series circuit substantially at the time the switch contacts are carrying a minimum current and an actuating winding for said switch energized from a source of direct current, the circuit of said winding being intermittently opened and closed by said switch.

2. In an electric system for converting direct current into alternating current, said system having a transformer with input and output

windings, a source of direct current supply, a series input circuit including said input winding, a capacitor and a vibratory reed switch having movable contacts on said reed cooperating with stationary contacts to alternately connect said input circuit including said input winding and capacitor with said source of direct current in opposite directions, the vibrating frequency of said reed being substantially the same as the frequency to which said series circuit is tuned to effect the opening of said circuit substantially at the time the switch contacts are carrying a minimum current, and a circuit including an energizing winding for said switch independent of said primary and capacitor circuit and intermittently opened and closed by said switch.

3. In an electric system for converting direct current into alternating current, said system having a transformer with input and output windings, a source of direct current supply, a series input circuit including said input windings, a capacitor and a vibratory reed switch having movable contacts on said reed cooperating with stationary contacts to alternately connect said input circuit including said series input winding and capacitor with said source of direct current in opposite directions, the vibrating frequency of said reed being substantially the same as the frequency to which said series circuit is tuned to effect the opening of said circuit substantially at the time the switch contacts are carrying a minimum current and an actuating winding for said switch energized from said source and having its circuit intermittently opened and closed by said switch.

4. In an electric system for converting direct current into alternating current, said system having a transformer with input and output windings, a source of direct current supply, a series input circuit including said input winding, a capacitor and a vibratory reed switch having movable contacts on said reed cooperating with stationary contacts to alternately connect said input circuit including said series input windings and said capacitor with said source of direct current in opposite directions, the vibrating frequency of said reed being substantially the same as the frequency to which said series circuit is tuned to effect the opening of said circuit substantially at the time the switch contacts are carrying a minimum current, and an independent circuit energized from said source and including a winding for said switch and alternately opened and closed by said switch.

5. In an electric system for converting direct current into alternating current, said system having a transformer with input and output windings, a source of direct current supply, a series input circuit including said input windings, a capacitor and a vibratory reed switch having movable contacts on said reed cooperating with stationary contacts to alternately connect said input circuit including said input winding and capacitor with said source of direct current and reverse the polarity of the circuit through the capacitor and winding, the vibrating frequency of said reed being substantially the same as the frequency to which said series circuit is tuned to effect the opening of said circuit substantially at the time the switch contacts are carrying a minimum current, and an actuating winding for said switch energized from said source of direct current, the circuit of said winding being intermittently opened and closed by said switch.

6. In an electric system for converting direct

current into alternating current, said system having a transformer with input and output windings, a source of direct current supply, a series input circuit including said input winding, a capacitor and a vibratory reed switch having movable contacts on said reed cooperating with stationary contacts to connect said input circuit with said source and reverse the polarity of the current from said source through the primary winding and capacitor, the vibrating frequency 10

of said reed being substantially the same as the frequency to which said series circuit is tuned to effect the opening of said circuit substantially at the time the switch contacts are carrying a minimum current, and a circuit independent of said primary winding including a winding for said switch and intermittently opened and closed by said switch.

WILLIAM W. GARSTANG.
